UNITED STATES PATENT OFFICE.

HENRY J. PAIN, OF NEW YORK, N.Y.

TOY.

Specification of Letters Patent.

Patented Jan. 15, 1918.

1,253,715.

Application filed April 6, 1916. Serial No. 89,351.

To all whom it may concern:

Be it known that I, HENRY J. PAIN, a citizen of the United States, residing in the borough of Manhattan, city, county, and State of New York, have invented an Improvement in Toys, of which the following is a specification.

At the present time when a greater part of the so-called civilized world is at arms every one, even children, is interested somewhat, at least, in warfare. The object of my present invention is the provision of simple inexpensively constructed toy for the amusement of children and in carrying out the same I preferably employ a sheet of suitable material on one surface of which is pictured a battleship, a fort or other representation having armament of one kind or another, and the sheet suitably provided with holes or apertures representing the mouths of the guns adapted to receive harmless toy fuses each so constructed that when lighted at one end it will burn emitting intermittently flashes of light in such a manner as to represent the firing of a gun, and the invention in the present case relates more particularly to the toy fuse.

In the drawing, Figure 1, is an elevation of a form of toy illustrating the invention, and

Fig. 2, is a partial cross section illustrating the manner in which the fuse is inserted in any of the apertures representing the mouths of the guns.

As illustrated in the drawing the toy, as a new article of manufacture, comprising the present invention, is made of a sheet of cardboard, asbestos, paper or other similar material indicated at 10 and having on one surface thereof a representation of a battleship as shown at 11. It is understood, however, that while as herein indicated I have illustrated the invention as applying to a battleship any fortification may be illustrated and used for the same purpose in a toy. In any form of the invention a plurality of holes 12 are provided in the sheet so that each hole represents a mouth of a gun as shown at 13.

In conjunction with the representation of the battleship or any fortification I employ a fuse shown at 14. This fuse is made of a mixture of any well known pyrotechnic material and any slow burning substance, this mixture being placed in a suitable

wrapper preferably made of paper with the ends twisted as illustrated in the drawing so that the same may be inserted and supported at one end in any one of the holes 12 in the sheet which may be maintained in an upright or nearly vertical position by a brace 15, of any desired form suitably attached to the reverse side thereof. In the use of the toy after the same has been set in position and the fuses are placed thereon, one or more of the fuses may be lighted and as hereinbefore stated each fuse burns slowly due to the slow burning material and intermittently emits harmless flashes of light to represent the firing of a gun.

The desired effect in producing the flashes of light from the fuse or cartridge is obtained by constructing the fuse of any well known firework composition, and a slow burning material, this mixture as hereinbefore stated being contained in a suitable paper wrapper to form the fuse or cartridge. The pyrotechnic composition may consist of a nitrate, shellac or sulfur, aluminum or metallic magnesium and nitrate of potash, while the slow burning material employed may be of red gum, kauri dust or brimstone or any other similar material to produce the same results. It will be understood that the number and frequency of the flashes of light will depend upon the quantity of slow burning material added to the pyrotechnic composition.

I claim as my invention:

1. As a new article of manufacture, a flashing toy cartridge consisting of a composition of powdered pyrotechnic material and a powdered slow burning substance, and a wrapper for containing said composition so that when lighted the cartridge burns emitting flashes of light at relatively long intervals.

2. As a new article of manufacture, a flashing toy cartridge consisting of pyrotechnic powdered composition, a powdered slow burning substance mixed therewith, and a wrapper for containing said pyrotechnic composition and slow burning substance so that when lighted the cartridge is consumed slowly with the slow burning material igniting the pyrotechnic material at relatively long intervals causing the same to emit intermittent flashes of light.

3. As a new article of manufacture, a flashing toy cartridge comprising a pow-

dered pyrotechnic composition of nitrate barium, shellac, aluminum, and nitrate of potash, a suitable quantity of powdered red gum, as a slow burning substance, and a wrapper in which the mixture is contained so that when lighted the cartridge is consumed slowly with the slow burning ma-

terial igniting the pyrotechnic material at relatively long intervals causing the same to emit intermittent flashes of light. 10
Signed by me this 21st day of March, 1916.

HENRY J. PAIN.
